(57) **CLAIM**

The ornamental design for a nail polish dryer, as shown and described.

DESCRIPTION

FIG. 1 is a top perspective view of a nail polish dryer, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the nail polish dryer, shown in another configuration.

The broken lines in the drawings illustrate the portions of the nail polish dryer, which form no part of the claimed design.
